ATTORNEY.

UNITED STATES PATENT OFFICE.

CATHERINE M. BUHRMAN, OF GRACEHAM, MARYLAND, ASSIGNOR OF ONE-FOURTH
TO HARRY W. STULL, ONE-FOURTH TO REUBY M. STULL, AND ONE-FOURTH TO
ELEANOR R. STULL, ALL OF ROCKY RIDGE, MARYLAND.

WINDOW-VENTILATOR.

1,390,878.

Specification of Letters Patent. Patented Sept. 13, 1921.

Application filed November 23, 1920. Serial No. 426,022.

To all whom it may concern:

Be it known that I, CATHERINE M. BUHRMAN, a citizen of the United States, residing at Graceham, in the county of Frederick and State of Maryland, have invented certain new and useful Improvements in Window-Ventilators; and I do hereby declare the following to be a full, clear, and exact description of the invention, such as will enable others skilled in the art to which it appertains to make and use the same.

This invention relates to new and useful improvements in window ventilators and has for its primary object the provision of a transparent protecting element operating in conjunction with the screens for excluding rain, snow, dust, etc. and thereby prevent such from entering the room through the screen, but which will permit free circulation of air.

Another object of this invention is the provision of means whereby the protecting element may be adjusted in relation to the screen for regulating the circulation of air and which means is capable of retaining the protecting element in any of its adjusted positions and will permit of the device to be folded into a comparatively small article when desiring to store the same in a small space.

A further object of this invention is the provision of a window ventilator of the above stated character which will be simple, durable and efficient, and which may be manufactured and sold at a comparatively low cost.

With these and other objects in view as will become more apparent as the descriptions proceeds, the invention consists in certain novel features of construction, combination, and arrangement of parts as will be hereinafter more fully described and claimed.

For a complete understanding of my invention, reference is to be had to the following description and accompanying drawings, in which:—

Figure 1 is a front elevation, illustrating a window ventilator constructed in accordance with my invention.

Fig. 2 is a sectional view taken on the line 2—2 of Fig. 1,

Fig. 3 is a section view taken on the line 3—3 of Fig. 1,

Fig. 4 is a detail sectional view illustrating adjusting strips for the screen,

Fig. 5 is a fragmentary sectional view illustrating the connection between one of the adjusting members and the screen frame.

Referring in detail to the drawings, the numeral 1 indicates a window frame having the usual lower sliding sash 2. A screen 3 consisting of upper and lower longitudinally extending runs 4 is mounted within the window frame 1 below and in direct alignment with the movement of the window sash 2 and the latter is adapted to rest upon the upper run 4. The foraminous material 5 is secured to the upper and lower runs 4 and has its end edges bound by metallic strips 6. Adjusting members 7 are slidably connected to the upper and lower runs 4 by dove-tail tenons 8 fitting within dove-tail grooves 9 formed in said upper and lower runs 4. The adjusting members 7 are adapted to form the end members of the screen frame, and are capable of adjustment longitudinally on the upper and lower runs so that the screen may be adjusted to fit window frames of different sizes. The end edges of the foraminous material 5 have frictional contact with the adjusting members 7 to prevent flies and other insects from gaining access to the room by way of the screen.

A protecting element 10 consisting of a rectangular frame 11 is associated with the screen 3 and is connected to the lower run 4 of the screen by means of strap hinges 12 which rest upon the window sill 13. The frame 11 carries a transparent panel 14 of glass or any other material suitable for the purpose and said frame is adapted to project upwardly and outwardly of the screen so as to permit free circulation of air through the screen but will exclude dust, rain, snow, etc. The frame 11 is of a width and height greater than the screen as shown clearly in Fig. 1 and has connected to its side edges protecting elements 15 constructed from fabric or any other material suitable for the purpose and which is also secured to the side edges of the adjusting member 7 of the screen 3 so that the space between the side edges of the screen and protecting elements are closed, to prevent foreign matter from entering into the space between the protecting element and the

screen by way of the side edges of said protecting element. The connecting or side elements 15 being constructed of fabric or similar material will permit the protecting element 10 to be adjusted toward and from the screen as desired for the purpose of regulating the circulation of air.

An arm 16 is pivoted to the upper run 4 of the screen and is capable of swinging horizontally in either direction and carries a plurality of eyelets 17, any one of which is adapted to receive the free end of a hook 18 pivoted to the upper run of the frame 11, thereby providing a construction which will permit adjustment of the frame or protecting element 10 toward and from the screen and which will retain the protecting element in any of its adjusted positions. The arm 16 pivoted to the screen and the hook and the latter pivoted to the protecting element frame, provides a construction which will permit the protecting element to be folded in close proximity to the screen when desiring to store the device in a comparatively small 25 space.

A draining element 19 constructed from flexible water-proof material has one end secured to the lower run of the frame 11 by a metallic strip and fasteners and is 30 adapted to prevent water from draining into a room under the frame 11. The draining element 19 has its ends extended from the

frame 11 and secured to the protecting elements 15 by snap fasteners 20. The protecting elements 15 also are secured to the frame 35 11 and 4 by snap fasteners 21.

While I have shown and described the preferred embodiment of my invention, it will be understood that minor changes in construction, combination and arrangement 40 of parts may be made without departing from the spirit and scope of the invention as claimed.

Having thus described my invention what I claim is:—

A window ventilator comprising a screen adapted to be positioned in a window frame, a rectangular frame of a width and height greater than the screen hinged to said screen, flexible means connecting the ends of the 50 frame and screen together, a transparent panel carried by said frame, detachable and adjustable connections between the frame and the screen, a draining element secured to the lower portion of the frame and constructed of flexible water-proof material and having its ends extended and detachably connected to the flexible means.

In testimony whereof I affix my signature in presence of two witnesses.

CATHERINE M. BUHRMAN.
